UNITED STATES PATENT OFFICE.

SAMUEL FINE, OF PHILADELPHIA, PENNSYLVANIA.

HAND PLANE.

Application filed March 22, 1924. Serial No. 701,008.

To all whom it may concern:

Be it known that I, SAMUEL FINE, a citizen of the United States, residing at Philadelphia, in the county of Philadelphia and

5 State of Pennsylvania, have invented a certain new and useful Hand Plane, of which the following is a specification.

This invention, generally stated, relates to a hand plane and has more especial relation 10 to means for adjusting the cutting blade thereof.

The principal object of the present invention is to provide a single, efficient and comparatively inexpensive arrangement of parts 15 whereby a rapid and accurate adjustment of cutting blade may be readily accomplished. A further object resides in the provision of eccentrically arranged means for attaining parallel relation of parts between the cutting 20 edge of a blade and the slot in the plane base and in the provision of other means operatively connected with respect to the eccentrically arranged means for adjusting said blade toward or away from the slot of the 25 plane base. Other and further objects reside in the provision of general arrangement, combination and connection of parts for attaining the results sought by the foregoing objects.

30 The invention consists of the novel construction hereafter described and finally claimed.

The nature, characteristic features and scope of the invention will be more fully 35 understood from the following description taken in connection with the accompanying drawings forming part hereof, and in which:

Fig. 1, is a view in perspective of a hand plane embodying features of the invention, 40 the cover plate being detached.

Fig. 2, is a view in central section of the plane including said cover plate.

Fig. 3, is a view in perspective illustrating 45 a portion of the plane bed.

Fig. 4, is a view in perspective of the plane cover plate, and

Fig. 5, is a view in plan of the cutting blade.

For the purpose of illustrating my invention 50 I have shown in the accompanying drawings one form thereof which is at present preferred by me, since the same has been found in practice to give satisfactory and reliable results, although it is to be understood that the various instrumentalities of 55 which my invention consists can be variously

arranged and organized and that my invention is not limited to the precise arrangement and organization of the instrumentalities as 60 herein shown and described.

Referring now to the drawings in detail, the numeral 1 designates the base plate of a hand plane of the type made principally or wholly of metal. The base plate 1 is provided with the usual cross-slot 2. Fixed to and carried by the base plate 1 is a bed plate 3 which is arranged at an inclination to the base plate. This bed plate 3 is flanged as at 4, which flanges are downwardly extended. The numeral 5 designates an adjusting screw 65

arranged in parallelism with the bed plate 3 and is journalled as at 6 in the rear flange of the bed plate and is also journalled as at 7 in a lug 8 projected from the under face of the bed plate 3. The bed plate is slotted upon its upper face as at 9, see Fig. 3, and is further milled out substantially V-shaped fashion as at 10 for a purpose to presently appear. The numeral 11 designates a cutter 70

blade the cutting edge 12 of which is adapted to coact with the cross-slot 2 of the base plate. The cutting blade 11 is apertured as at 13 to accommodate an eccentric 14 supported by an eccentric pin 15 mounted upon a carrier 16. This carrier has screw-threaded 75

relation with, and is adapted to be operable endwise by means of the screw 5. Thus as the cutter blade 11 is moved toward or away from the cross-slot 2 of the base plate 80 the carrier 16 moves a corresponding distance in the same direction. In order to provide lateral, adjusting movement for the cutting blade, use is made of eccentric 14.

The latter is provided with an operating handle or lever 17 connected to the eccentric 85 and accommodated within the V-shaped portion of the bed plate. By shifting the handle or lever 17, in the proper direction, the cutting edge of the blade 11 may be moved laterally to attain parallelism with the cross-slot 2. This movement is possible because 90

the blade is pivoted adjacent its cutting edge by means of set screw 18 which secures the cover plate 19 to the base plate and obviously maintains the cutting blade in abutting relation with the base plate. In order that the 95

cover plate 19 may be readily applied and removed, an opening 20, in communication with a slot 21, is provided in said plate. By placing opening 20 over thumb-screw 18 100

and then shifting the cover toward the cross-slot 2, the slot 21 is caused to cooperate with 105

the stem of the thumb screw 18, so that when the thumb screw is tightened, the cover is clamped with respect to the bed plate. The cutting blade is also provided with an opening 22 in communication with a slot 23. To position the cutting blade, the aperture 22 is first fitted over thumb-screw 18 and then the blade moved in a direction toward the cross slot 2 in the base plate so that the slot 23 engages with the stem of the thumb screw 18. The cover plate at its lower end abuts against the cutter blade and the upper portion is arched as at 24 to cover the eccentric connection. A set screw 25 is employed to maintain screw 5 against displacement.

It will now be apparent that I have devised a novel and useful construction which embodies the features of advantage enumerated as desirable in the statement of the invention and the above description and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

Having thus described my invention,

what I claim as new and desire to secure by Letters Patent, is:

A plane of the character stated comprising a base plate having a cross slot therein, a bed plate having a lug upon its under side at the lower end thereof and having a depending flange at its opposite end, the said bed plate having a longitudinal slot arranged intermediate of said lug and flange, a longitudinally slotted cutting blade mounted upon said bed plate, an adjusting screw rotatably supported by said lug and flange, an eccentric carrier movable with said adjusting screw along the slot in said bed plate, an eccentric operatively connected with said cutting blade and carrier, a cover plate arranged upon said cutting blade, and a set screw passing through said cover plate and the slot of the cutting blade for coacting with the lug of the bed plate to secure said cover plate in position and to form a pivot for the cutting blade, whereby in the movement of said adjusting screw the cutting blade may be moved toward said cross slot and in the movement of said eccentric may be moved about its pivot point.

In testimony whereof, I have hereunto signed my name.

SAMUEL FINE.
